UNITED STATES PATENT OFFICE.

HERBERT DUUNDERDALE, OF CLEVELAND, OHIO.

MOVABLE STEP FOR VEHICLES.

1,239,892.

Specification of Letters Patent. Patented Sept. 11, 1917.

Application filed March 9, 1916. Serial No. 83,010.

To all whom it may concern:

Be it known that I, HERBERT DUUNDERDALE, a citizen of the United States, residing at Cleveland, in the county of Cuyahoga and 5 State of Ohio, have invented certain new and useful Improvements in Movable Steps for Vehicles, of which the following is a full, clear, and exact description, such as will enable others skilled in this art to make and 10 use the same.

My invention has reference to an improved movable step for railway cars, and has for its main objects to improve and simplify the construction and increase the 15 efficiency and durability of devices of this character; to provide a movable step that is automatic in movement between its operative projecting and inoperative retract- 20 ed positions; the provision of a step of this character whose component parts are few in number and which may be readily applied to a car of standard construction.

The invention also contemplates certain novel details of construction, combination 25 and arrangement of parts of the improved device, whereby certain advantages are attained, as will be more fully described hereinafter, and pointed out in the claims.

These, together with such other objects 30 as may hereinafter appear, or are incident to my invention, I obtain by the construction illustrated in preferred form in the accompanying drawings, wherein:—

Figure 1 represents a view in perspective 35 illustrating the application of my improved movable step to a car, the step being in operative projecting relation with reference to the car steps;

Fig. 2 is a similar view showing the step 40 in its retracted inoperative position;

Fig. 3 represents a front view in elevation of the steps in Fig. 1; and

Fig. 4 is a side elevation of Fig. 3.

Referring to the drawings, the numeral 5 45 indicates the car body, 6 the platform, 7 the end timber, 8 the fixed steps having the customary inner side piece 9 secured to the car body and the outer side piece 10 de- 50 pending from the end timber 7, and 11 the trap door hinged to the car body and de- signed when lowered to occupy the position shown in Fig. 2 to close off the steps from use by the passengers when the car is in motion.

55 The movable step is indicated in the various figures of the drawings by the nu-

meral 12, and as shown is terminally carried by the side bars 13, the latter extending through the inclined slideways 14 formed by the sockets of the guide members 15 60 which are secured to the outer faces of the side pieces 9 and 10. Disposed in the path of the trap door 11 is an actuating bar 16 mounted for vertical movement in a slot 17 65 formed in that portion of the end timber 65 adjacent the steps 8. The upper end of the bar is flanged over at 18, and its lower end projecting through the lower terminal of the slot 17 is there provided with a stud 19 70 slidably engaging the wall of an elongated slot 20 which is formed in the free end of a fulcrum lever 21 pivotally mounted at 22 on the side piece 10.

A link 23 is provided to connect the other 75 end of the fulcrum lever 21 with the upper extension 13^a of the outer bar 13 and in a manner whereby on depression of the actuating member 18 by the trap-door, when lowered, the bars 13 rise in their inclined guides and raise the movable step to its inoperative position under the lower fixed 80 step 8 as indicated clearly in Fig. 2. Stops 24 are provided on the extensions 13^a of the bars 13 to take against the upper faces of the guide sockets 14 in order to limit the 85 downward gravity movement of the movable step 12 when the trap-door is raised (Figs. 1 and 3).

Means are provided in order to equalize 90 the movement of the left hand inner end of the step 12 with that of the right hand end, and to relieve it of stress and binding particularly during the upward movement of the step. With this end in view the upper 95 portions of the bars 13 are formed on their under faces with rack teeth 25 designed to be engaged by the spur teeth of the gears 26. These gears have synchronous rotation through, and are mounted on a gear shaft 27 which extends behind the steps 8 and 100 their risers and is terminally carried in bearings 28 secured to the inclined under faces of the side pieces 9 and 10. In this manner no stress is unduly placed upon any portion of the movable step and any possible binding of the side bars 13 in their 105 guides is positively overcome.

The operation of raising and lowering my movable step is automatic and positive in character, and furthermore is under the 110 control of the trainmen, since to raise the step all that is required is to drop the trap

door. From the description thus far made it will be obvious that the door in falling depresses the actuating member 18 which in turn actuates the fulcrum lever 21, link 23, and the bars 13, to raise the step into its retracted position and clear of any obstructions. On raising the trap-door, the step gravitates into its extended operative position.

10 From the foregoing description the essential features, elements and operation of my movable step, together with its simplicity and adaptability to standard car ends, and other advantages thereof, will be clearly apparent to those skilled in the art.

I do not intend to restrict myself to the exact details or to the precise arrangement of the various parts, as shown, as it is manifest that variations may be made on structural features and arrangement without departing from the spirit and scope of my invention and improvements. I therefore reserve the right to all such variations as properly fall within the scope of my invention and the terms of the following claims.

What I claim is:

1. In combination with the stationary car steps and a trap-door therefor, of an extensible step provided with movable rack members mounted on the sides of said car steps, equalizing pinions engaging said rack members, and actuating means mounted independently of said pinions comprising a depressible bar operatively disposed in the path of said trap-door, said bar provided

with connections with one of said rack members and constructed and arranged to raise said extensible step on depression of said bar, and permitting the lowering of said step to its extended position upon the raising of said trap-door. 40

2. In combination with the stationary car steps and a trap door therefor, of an extensible step having movable rack bar members mounted on the sides of the car steps, shafted equalizing pinions engaging said rack bar members, one of said bars having a portion extending upwardly past its respective pinion, a vertically depressible actuating member having an upper portion disposed in the path of the trap door, and operative lever connections between said upwardly extending portion and the base of said actuating member. 45

3. In combination with the stationary car steps and a trap-door therefor, of a movable extensible step having inclined side hanger members, guides for said members mounted on the sides of said stationary steps, an actuating depressible member disposed in the downward path of the trap-door to be actuated thereby, a rocking lever having a lost motion connection with said depressible member and provided with a link connection with one of said hanger members, and an 60 equalizing mechanism for said members.

In testimony whereof I have hereunto signed my name and affixed my seal.

HERBERT DUNDERDALE. [L.S.]
